CIRCUIT INTERRUPTER

Andrew H. Bakken, Edgewood, Pa., assignor to Westinghouse Electric & Manufacturing Company, East Pittsburgh, Pa., a corporation of Pennsylvania

Application January 13, 1940, Serial No. 313,745

13 Claims. (Cl. 200—148)

This invention relates to improvements in circuit interrupters and, more particularly, to circuit breakers of the gas blast type. In the application of J. B. MacNeill et al., Serial No. 313,430, filed January 11, 1940, and assigned to the assignee of this application, is shown and described an air blast circuit interrupter in which the auxiliary gas pressure storage tank is utilized as a support for the interrupting and operating mechanisms. In accordance with the aforesaid application, a hollow insulator used to support the arc extinguishing structure also serves to direct an arc extinguishing blast of gas to the space between the separable contacts.

It is an object of the present invention to improve the operation of circuit interrupters of the aforesaid type by the provision of a contact structure that is simple in design, easy to operate and which enables an arc to be established directly across the discharge end of the hollow insulator utilized in supporting the arc extinguishing unit, thereby eliminating bends in the gas supply line from the pressure tank to the arc extinguishing unit and a loss of pressure.

It is a further object of the invention to provide a gas blast circuit breaker with a direct and substantially straight path for the blast of gas from the tank through the arc at substantially right angles thereto and without restrictions which would prevent the full flow of the blast of gas through the arc, and thereby make possible the use of as low a gas pressure in the tank as possible.

A more specific object of the invention resides in the provision of a hinged type moving contact structure for a breaker of the aforesaid type which provides a low resistance conducting path free of flexible shunts or sliding contacts.

Another object of my invention is to provide an arc extinguishing structure in the form of an arc chute for a gas blast type of circuit interrupter that is so arranged with respect to the contact assembly and the gas supply means thereto that the arc chute can be easily removed without disturbing the contact assembly or its operativeness for the purpose of enabling ready inspection of the condition of the contacts and/or making adjustments to the operating mechanism for the contacts.

A further object of my invention is to provide an improved pressure actuated operating mechanism for gas blast circuit breakers which incorporates mechanically actuated means for controlling the admission of an arc extinguishing blast of gas to the arc extinguishing structure

of the breaker. In this connection, it is contemplated to provide a separate gas blast control valve means for each arc extinguishing unit of a polyphase circuit breaker so as to eliminate the difficulties of gas flow normally encountered in a manifold conduit system utilizing but a single gas blast control valve for all phases of the breaker.

Other objects and advantages will appear in the following description, when taken in connection with the accompanying drawings, in which

Figure 1 is a front elevation view of a polyphase circuit interrupter embodying my invention,

Fig. 2 is a side elevation view of the circuit interrupter shown in Fig. 1, partially in section for more clearly illustrating the gas blast control and the operating mechanism, and

Fig. 3 is an enlarged fragmentary view partially in section showing a modified gas blast control arrangement.

Referring to the drawings, the reference numeral 3 designates a tank for storing gas, such as air, under pressure. Extending from the top 25 of the tank 3 are a plurality of, in this instance, three flanged conduits 5. Secured to the flanged portion of each conduit 5 is a metallic valve casing 7. Mounted upon the upper end of each valve casing 7 is a tubular insulator 9 which, in turn, has secured to its upper end an arc chute support 11 of insulating material. The support 11 also carries a stationary contact assembly 13 including a plurality of spring pressed contact fingers 15. A throat-like gas passage 17 extends 30 through the support 11 and is preferably coextensive with the passage through the tubular insulator 9. The throat-like passage 17 discharges 35 into an arc chute structure 19 having two generally parallel side walls 21 and 23. The side walls 40 21 and 23 are adapted to rest upon a support 11 and are secured thereto by a pair of transversely extending bolts 25 which are the sole means for holding the arc chute in place. Each arc chute 45 19 is generally of the type more fully shown and described in the application of L. R. Ludwig, et al., Serial No. 313,736, filed January 13, 1940, and assigned to the assignee of this application, but inasmuch as the arc chute is not claimed specifically in this application, it is deemed that a further description thereof is not necessary for the 50 understanding of the instant invention.

The forward side of each arc chute 19 is provided with a rectangular slot 27 at the lower end thereof through which a blade-like movable contact 29 may operate into and out of engagement

with the stationary contact fingers 15. The movable contact 29 is preferably of inverted L-shaped blade construction having a bifurcated arm 31, the two legs of which are pivoted at 33 to a conducting bracket 35 clamped about the tubular insulator 9. The pivotal connection 33 is of the high pressure type so that good electrical contact is maintained at all times between the bracket 35 and the arm 31. The right-hand side of bracket 35 is provided with an external circuit terminal 37. The stationary contact assembly 13 is also provided with an external circuit terminal indicated at 39. Thus when the interrupter is in the closed circuit position, as shown, an electrical circuit is made therethrough from the terminal 39, stationary contact 15, moving contact 29, contact arm 31, bracket 35, to the terminal 37.

Movement of the contact arm 31 about the pivot 33 in a counter-clockwise direction to actuate the interrupter to the open circuit position is accomplished by an operating mechanism generally indicated at 41. This operating mechanism is preferably of the gas pressure operated type and includes a cylinder 43, a piston therein (not shown) provided with a connecting rod 45 extending from the upper end of the cylinder. The connecting rod 45 is coupled by a pair of links 47 to a crank arm 49 secured to a cross shaft 51. The cross shaft 51, for example, may be journaled in suitable brackets 53 secured to the side of the pressure tank 3.

The cross shaft 51 has mounted thereon at spaced intervals three crank arms 55 which, in turn, are coupled by an insulating operating rod 57 to the moving contact arms 31 of the respective pole units. Gas under pressure is admitted to the cylinder 43 for actuating the interrupter to the open circuit position by a valve 59, the lower portion of which rests and is supported upon the flange 61 of a conduit 63, leading from the interior of the pressure tank 3. A similar control valve 65 is used for controlling the admission of gas from the pressure tank 3 to the cylinder 43 for closing the circuit interrupter. The valve 65 rests upon, and is supported by, a flange 67 of the conduit 69 leading into the storage tank 3. The valves 59 and 65 are secured to the cylinder 43 so as to form a unit and are supported solely by the conduits 63 and 69 carried by the tank 3. Actuation of the valves 59 and 65 may be by any suitable means, such as electromagnetic, pneumatic, or combinations of both.

Each of the crank arms 55 is provided with a cam 71 which is adapted to engage a roller 73 carried by a bell crank 75. The bell crank 75 is operatively coupled at 77 to the end of a valve stem 79 extending through the valve casing 7. The lower end of the valve stem 79 carries a valve 81 which normally seals off the pressure tank 3 from the hollow insulator 9 and the arc chute 19.

It will thus be seen that as gas under pressure is admitted to the operating cylinder 43 by the valve 59, the connecting rod 45 will be moved downwardly, rocking the crank arm 49 in the counter-clockwise direction as viewed in Fig. 2. At the same time, the three crank arms 55 will also be rocked in the counter-clockwise direction, as viewed in Fig. 2, so as to move the operating rods 57 downwardly, causing them to actuate the contact arm 31 and their associated moving contacts 29 to the open circuit position. It will be noted that shortly prior to separation of the moving contacts 29 from the stationary contact fingers 15, the cam 71 will have caused bell crank

75 to rotate in the clockwise direction, depressing the valve stem 79 to cause valve 81 to emit a blast of gas from the tank 3 through the insulator 9 into the gas discharge throat 17 for extinguishing the arc formed upon separation of the contacts 15 and 29. It will be noted that cam 71 has a high side 83 which maintains the valve 81 open during a predetermined time interval while the moving contacts 29 are being moved to the open circuit position. As each moving contact 29 reaches its full open circuit position, the roller 73 will have moved beyond the cam surface 83 to again permit the valve 81 to close, thus positively shutting off the supply of gas through each interrupter.

It will be observed that the gas blast for extinguishing the arc is directed in a substantially straight path from the pressure tank 3 through the tubular insulator 9 into engagement with the arc, thereby avoiding turbulence or eddies in the gas conducting system and a consequent loss of pressure.

Closing movement of the interrupter is effected by admitting compressed gas to the cylinder 43 through the valve 65, which moves the connecting rod 45 upwardly, causing the crank arm and the cross shaft 51 to rotate in a clockwise direction as viewed in Fig. 2, and consequently also causing the crank arms 55 to actuate the operating rods 57 upwardly so as to rock the contact arms 31 to the closed circuit position. Shortly following initiation of the closing movement, the roller 73 will again be actuated by the cam surface 83 to cause valve 81 to be opened to cause a blast of gas to be directed through the insulator 9 in the path between the closing contacts. This blast of gas is discontinued as soon as the moving contacts 29 make contacting engagement with the stationary contacts 15 and the roller 73 is again positioned as shown in the drawings. During the closing operation of the interrupter, the crank arms 55 are rotated in a clockwise direction until they engage stop members 85 so positioned that the crank arms 55 and their associated operating rods 57 form a slightly overcenter toggle relation with each other, thereby maintaining the moving contacts 29 positively locked in the closed circuit position.

In order to conserve gas during the operation of the interrupter, I have provided a modified gas blast control arrangement as shown in Fig. 3. In the arrangement shown in Fig. 3, the crank arm 55 has been replaced with an arm 87. The crank arm 87 differs from crank arm 55 in that the former has a collapsible cam portion 89 whereas the cam portion 83 of the latter is fixed. The cam portion or member 89 is coupled to the crank arm 87 by two pairs of short links 91 and 93 and pivot pins 95 and 97. A spring 99 disposed about each pivot pin 95 biases the cam member 89 in a clockwise direction with respect to pins 95 against a stop 101 which is in this instance an integral part of the crank arm 87.

Thus when the cam member 89 is against the stop 101 it is in an extended position with respect to the shaft 51 and operative with respect to the roller 73, against which it moves during the opening operation of the interrupter. During the opening operation, the operating mechanism 41 causes shaft 51 to be rotated in a counter-clockwise direction to bring cam 89 into engagement with the roller 73 so as to rock the bell crank 75 in a clockwise direction, thereby actuating the valve 81 to the open position, which

admits an arc-extinguishing blast of gas from the tank 3 into the tubular insulator 9. The cam member 89 is shaped similarly to cam 83, previously described, so that when the contacts 29 have reached full open circuit position, the valve 81 is permitted to close, causing discontinuance of the arc-extinguishing blast of gas.

However, during the closing operation, as crank arm 87 is rotated in a clockwise direction, the cam 89 will collapse upon being brought into forceful engagement with the roller 73 and take a position as shown in dotted lines in Fig. 3. In this position the cam 89 is ineffective to actuate the roller 73 and the bell crank 15, thereby permitting the valve 81 to remain closed during the entire circuit closing operation. Just prior to engagement of the moving contacts 29 with the stationary contacts 15, the cam 89 is brought into a position to clear the roller 73. Upon reaching this position, the springs 99 will rotate the links 91 and 93 in a clockwise direction to again extend the cam 89 and bring it into engagement with the stop 101, so that the cam will be operative to actuate the valve 81 during the next opening operation. Thus by making the cam 89 of collapsible form a considerable saving in compressed gas is effected in that the arc extinguishing blast is provided only during the circuit opening operation.

Although I have shown and described a particular circuit interrupting structure, it is to be understood that the same is for the purpose of illustration and that changes and modifications may be made by those skilled in the art without departing from the spirit and scope of the appended claims.

I claim as my invention:

1. In a gas blast circuit interrupter, a tank for storing gas under pressure, a hollow insulator supported by said tank, stationary contact means mounted on the free end of said insulator, a coacting movable contact pivotally mounted upon said insulator intermediate the ends thereof and having its contact portion movable across the free end of said insulator in a path generally at right angles to the longitudinal axis of said insulator, operating means for moving said movable contact into and out of engagement with said stationary contact means mounted on the free end of said insulator to make and break the connected circuit, arc extinguishing means also mounted on the free end of said insulator, and means for causing a blast of gas to flow from said tank through said hollow insulator during at least the opening movement of said movable contact, said blast of gas driving any arc formed at said contact means into said arc extinguishing means.

2. In a gas blast circuit interrupter, a tank for storing gas under pressure, a straight hollow insulator supported upon and extending upwardly from said tank, stationary contact means mounted upon the upper end of said insulator, a coacting contact movable across the open upper end of said hollow insulator to establish an arc generally perpendicular to the longitudinal axis of said hollow insulator, a contact arm pivotally mounted upon said insulator for carrying said movable contact, operating means for moving said contact arm to open and closed position, and valve means for causing a blast of gas under pressure to flow through said hollow insulator and across the arc drawn across the open end thereof.

3. In a gas blast circuit interrupter, a tank for storing gas under pressure, a straight hollow insulator supported substantially vertically by said tank, stationary contact means mounted on the free end of said insulator, a coacting contact movable across the open end of said hollow insulator to establish an arc generally at right angles to the longitudinal axis of said hollow insulator, operating means for moving said movable contact to open and closed circuit positions, a valve disposed at the juncture of said hollow insulator with the tank for controlling the flow of gas thereinto from said tank, and means for operating said valve to open and closed positions.

4. In a gas blast circuit interrupter, a tank for storing gas under pressure, a straight tubular insulator mounted from said tank, a stationary contact supported by the free end of said insulator and to one side of the open end thereof, a terminal member supported intermediate the ends of said insulator, a movable contact hinged to said terminal member for swinging movement to open and closed circuit position, said moving contact having a portion movable across the open end of said insulator in a path generally perpendicular to the longitudinal axis of said insulator, means for operating said movable contact to open circuit position to establish an arc across the open end of said insulator, and means for admitting a blast of gas from said tank into said insulator to extinguish the arc.

5. In a gas blast circuit interrupter, a tank for storing gas under pressure, a tubular insulator mounted substantially vertically upon said tank, a stationary contact supported upon the upper end of said insulator and to one side of the open end thereof, a terminal member supported intermediate the ends of said insulator, a movable bridging contact member hinged to said terminal member for swinging movement into and out of engagement with said stationary contact, said bridging member having a contact portion movable across the open end of said insulator in a path at substantially a right angle to the axis of the passage through the insulator, an arc chute vertically mounted over the free end of said tubular insulator for confining said arc, and means for causing a blast of gas to flow from said tank through said tubular insulator to extinguish said arc, said blast of gas flowing in substantially a straight line from said tank through said tubular insulator, across the arc and into said arc chute.

6. In a multi-phase gas blast circuit interrupter, a tank for storing gas under pressure, a plurality of tubular insulators mounted from said tank, separable contact means for drawing an arc adjacent the open end of each of said insulators, said tubular insulators providing direct paths for the flow of individual blasts of gas from said tank to said arcs, operating means for actuating said separable contact means, individual valve means for each path, and single means for simultaneously actuating said individual valve means for controlling the flow of gas in each of said paths and to provide a uniform flow of gas to all of said arcs.

7. In a multi-phase gas blast circuit interrupter, a tank for storing gas under pressure, a plurality of tubular insulators mounted from said tank, separable contact means for drawing an arc across the open end of each of said insulators, said tubular insulators providing straight paths for the flow of individual blasts of gas from said

tank to said arcs, operating means including a rock shaft for actuating said separable contact means, said rock shaft being supported for rocking movement upon the side of said tank, a valve at the base of each tubular insulator for controlling the flow of gas from said tank through each of said insulators, and means carried by said rock shaft and operable in response to rocking movement thereof to simultaneously operate said valves.

8. In a circuit interrupter, a tank for storing gas under pressure, separable contacts for making and breaking the connected circuit, a pressure actuated operating means for said contacts including a cylinder, a piston movable in said cylinder, a contact opening valve operable for admitting gas from said tank to said cylinder to actuate said piston and cause said contacts to be opened, a contact closing valve operable for admitting gas from said tank to said cylinder to actuate said piston and cause said contacts to be closed, said opening and closing valves being secured to said cylinder to form a unit assembly, and conduit means joining said tank with said valves, said conduit means serving as the sole support for said unit assembly.

9. In a gas blast circuit interrupter, a source of gas under pressure, separable contacts for establishing an arc, operating means for actuating said contacts to open and closed circuit positions, valve means for controlling the flow of gas from said source through the arc, and cam means carried by said operating means and a follower movable over the face of the cam for actuating said valve means, said cam means having said face on which the follower is movable collapsible during movement in one direction to open said valve means only during the opening movement of said operating means.

10. In a circuit interrupter, a tank for storing gas under pressure, separable contacts to establish an arc, operating means for actuating said contacts to open and closed circuit positions, valve means for admitting a blast of gas from said tank to said contacts, valve operating means associated with said contact operating means, said valve operating means including a cam having a collapsible portion and a follower movable over the face of said collapsible portion for actuating said valve means, means biasing and holding said collapsible portion in said extended position during movement of said contact operating means to the open circuit position to cause said collapsible portion to actuate said follower to open and close said valve means in a predetermined manner, said holding means being arranged to permit movement of said collapsible

portion to the collapsed position during movement of said contact operating means to the closed circuit position to actuate said valve means in a different manner.

6 11. In a multi-phase gas blast circuit interrupter, a plurality of pairs of separable contacts, a plurality of arc chambers each of which receives the arc drawn upon separation of one of said pairs of contacts, a common tank for 10 holding gas under pressure for extinguishing all of said arcs, a plurality of separate conduits each of which extends directly from said common tank to one of said arc chambers to provide an individual blast of gas from said tank to extinguish the arc drawn by one of said plurality of pairs of contacts, a plurality of blast valves each of which controls the blast of gas through one of said plurality of separate conduits, and means for jointly operating said plurality of blast valves 15 upon separation of said plurality of pairs of contacts.

12. In a multi-phase gas blast circuit interrupter, a plurality of pairs of separable contacts, a plurality of arc chambers each of which receives the arc drawn upon separation of one of said pairs of contacts, a common tank for holding gas under pressure for extinguishing all of said arcs, a plurality of separate conduits each of which extends directly from said common tank to one of said arc chambers to provide an individual blast of gas from said tank to extinguish the arc drawn by one of said plurality of pairs of contacts, a plurality of blast valves each of which controls the blast of gas through one of 20 said plurality of separate conduits, a common operating device for causing separation of all of said plurality of pairs of separable contacts, and means mechanically actuated by movement of said common operating device for jointly operating said plurality of blast valves upon separation of said plurality of pairs of contacts.

13. In a multi-phase gas blast circuit interrupter, tank means for storing gas under pressure, a plurality of tubular insulators extending from said tank means, separable contact means for drawing an arc adjacent the open end of each of said insulators, said tubular insulators providing direct paths for the flow of individual blasts of gas from said tank means to said arcs, operating means for actuating said separable contact means, individual valve means for each path, a common valve opening means mechanically driven from said operating means for simultaneously actuating said individual valve means for controlling the flow of gas in each 30 of said paths.

ANDREW H. BAKKEN.
